(57) **CLAIM**

The ornamental design for an M-shaped lens for an LED lighting fixture, as shown and described.

DESCRIPTION

FIG. 1 is a perspective view of the top of the M-shaped lens for an LED lighting fixture from a left side;

FIG. 2 is a perspective view of the top of the M-shaped lens for an LED lighting fixture of FIG. 1 from a right side;

FIG. 3 is a perspective view of the bottom of the M-shaped lens for an LED lighting fixture of FIG. 1 from a left side;

FIG. 4 is a perspective view of the bottom of the M-shaped lens for an LED lighting fixture of FIG. 1 from a right side; and,

FIG. 5 is an enlarged end view of the M-shaped lens for an LED lighting fixture of FIG. 1, as mounted in an LED lighting fixture.
